TRICK SHOT GUN

Ralph M. Crosby and Abdenoor Kander, Los Angeles, and Robert J. Mortenson, Los Alamitos, Calif., assignors to Ideal Toy Corporation, Hollis, N.Y.

Filed Feb. 1, 1961, Ser. No. 66,355

5 Claims. (Cl. 124—27)

This invention relates to a toy gun and more particularly to a spring operated dart shooting gun.

The concept of this invention features the use of a novel arrangement of darts whereby an "over the shoulder" trick shot is facilitated.

When attempting to aim a gun or direct a projectile at a target behind the shooter's head, it is generally necessary to employ a mirror or mirrored surface. Since heretofore the mirror had to be supported by one hand of the shooter, only the other hand was available for aiming and holding the gun on the target, which is quite different. It is therefore an object of the invention to provide means for facilitating the aiming and leveling of a gun so as to ensure better accomplishment of trick shots.

The present invention resides in a toy gun which can be used for shooting darts or like projectiles which are generally of a harmless nature through the use of a front hand grip provided with a trigger for actuating the firing mechanism of the gun while alternatively a rear hand grip which has another trigger associated therewith which can be used for firing the gun during trick shots.

A further object of the invention resides in the provision of a novel firing train for use in actuating the firing lever of the gun whereby either of two triggers can be alternatively used for actuating the firing lever for releasing the firing spring.

An important feature of the invention resides in the novel breech configuration for a gun wherein a shoulder rest is provided between front and rear hand grips.

A still further object of the invention is to provide a toy gun which may be manufactured out of various readily available materials such as any of the commercially available synthetic plastic resins, which employs parts which can be assembled in mass production with great facility, which is inexpensive to manufacture thereby permitting wide distribution of a highly entertaining toy gun for children at a relatively low cost, and which is simple in construction and substantially fool-proof in operation.

A further feature of the invention is the provision of a novel gun-sight for use in combination with the other features of this toy gun which is equipped with a mirrored surface and which sight has means provided for forming cross hairs in conjunction with the mirrored surface so that the target can be easily sighted and aligned in the sight.

These, together with the various ancillary objects and features of the invention, which will become apparent as the following description proceeds, are attained by this toy gun, a preferred embodiment of which has been illustrated in the accompanying drawing, by which way of example only, wherein:

FIG. 1 is a perspective view of the toy gun comprising the present invention;

FIG. 2 is a front elevational view of the toy gun;

FIG. 3 is a rear elevational view of the gun;

FIG. 4 is a perspective view of the firing train employed in this invention;

FIG. 5 is a longitudinal sectional view of the toy gun illustrating the firing mechanism in a cocked position;

FIG. 6 is a partial sectional detailed view of the gun illustrating the firing mechanism just after the trigger has been actuated.

2

With continuing reference to the accompanying drawings wherein like reference numerals designate similar parts throughout the various views, reference numeral 10 generally designates the toy gun comprising the present invention which includes a barrel 12 and a breech portion 14. Because of the construction of the gun, no separate stock need be provided, the breech portion being elongated and extending between a forwardly arranged firing mechanism 16, a front hand grip 18, and a rear hand grip 20. Further, there are provided front and rear sights 22 and 24, as well as a shoulder rest 25 disposed between the front hand grip 18 and the rear hand grip 20.

The toy gun is adapted to shoot darts 28. Of course, other suitable projectiles may be employed but suction cup tipped darts are quite harmless and therefore very satisfactory for use in a children's toy and in the present toy gun 10.

The toy gun 10 is adapted to project the darts 28 against any suitable target with the shooter facing the target. Alternatively, the toy gun 10 can be used for trick shots whereby the weapon may be fired over the shoulder of the shooter with the shooter facing away from the target. This is accomplished by employing the sight 24 which has a mirrored surface 26 for enabling the shooter to view the target therein.

The barrel and the breech 14 may be integrally molded with each other if desired or may be made separately and secured together by any suitable means. In the embodiment shown, the breech 14 and barrel 12 are molded integrally with each other but in separate halves 30, 32 which are then joined in any suitable manner such as by bonding, or by fastening using pins, bolts, or the like. The barrel 12 and the breech 14 can be manufactured out of various readily available materials such as metal, or synthetic plastic resins. Preferably, as in the embodiment shown, the two halves 30 and 32 of the combined breech 14 and barrel 12 as are separately molded and the front hand grip 18 and rear hand grip 20 are likewise integrally molded with the breech portion 14 in separate half portions.

The barrel 12 and firing mechanism 16 is preferably constructed in accordance with the patent to Albert M. Steiner, Patent No. 2,888,004, issued on May 26, 1959, for Toy Dart Gun. The barrel 12 has a bore provided with lands 36 and 38. The bore 34 forms a smooth surface defined by the lands 36 and 38 for guiding and confining coil spring 40 of the firing mechanism.

One end 41 of the spring 40 is connected to a rod 42 of a firing lever 44 which is pivotally mounted by a pin 46 within the breech portion 14. The firing lever 44 is of a generally Z shaped construction. The end 48 of the firing lever 44 has a detent depending therefrom. The other end of the firing lever 44 is configurated to form a catch 52 provided with a hook 54. The pin 46 permits the hook 54 to pivot into and out of the bore 34, a suitable slot 56 being provided in the breech portion 14 for allowing this pivoting action. The hook portion 54 is adapted to engage a collar 58 of a projectile 60 preferably in the form of a dart having an elongated shaft 62 terminating in a suction cup 64. A plurality of radial fins 66 project angularly from the shaft 62. Grooves are provided in the barrel, for receiving these fins 66 in the manner defined in the Steiner Patent No. 2,888,004 so as to permit the dart 60 to snugly fit therein without causing friction to retard the movement of the dart. The dart is provided with a portion 70 of enlarged cross sectional area forming a shoulder 72.

The end 43 of the spring 40 engages the rearmost portion 68 of the dart 60, fitting thereover and abutting the shoulder 70.

The other end 41 of the spring 40 may be force fitted

on the projecting finger 42 and abuts against the center portion 74 of the Z shaped firing lever 44, or the end 41 of the spring may be secured in any suitable manner as desired.

The firing lever 44 is moved into a cocked position by positioning the dart 60 in the barrel 12 and after engaging the end 68 thereof in the spring 40, pressing back on the spring will cause the firing lever 44 to assume a horizontal position and the collar 58 will ride over the surface 78 of the hook 56 until the hook engages the collar 58 to hold it in the position as is shown in FIG. 5.

The pin 46 is held in its desired position by means of mounting members 80 of any suitable configuration. Thus, the firing lever 44 is free to pivot about pin 46 as an axis.

A sear mechanism 82 is provided for actuating the firing lever 44. The sear mechanism is pivoted by means of a pin 84 which is secured by any suitable type of mounting member 86 within the breech portion 14. The sear includes a generally L shaped arm 88 as well as an opposed tapered arm 90.

A semi-cylindrical projection 92 is provided with an arcuate surface 94 which may ride on the bottom inner surface 100 of the breech portion 14. Angularly offset from the pin 84 and the semi-cylindrical projection 92 is another upwardly extending projection 102. Extending outwardly from the lower portion of the L shaped arm 88 is a substantially horizontally disposed projection 103 which is adapted to engage detent 50 so that pivoting action of the sear mechanism 82 will cause operation of the firing liner 44. The front hand grip 18 has a trigger finger opening 110 therein. A trigger 112 has a trigger portion 114 in alignment with the trigger finger opening 110 and adapted to be engaged by the trigger finger of the shooter which is inserted through the trigger opening 110. The trigger 112 is further provided with an end 116 having a contact surface 118 engageable with the tapered surface 120 of the sear mechanism 82. The trigger 112 is pivotally mounted in breech portion 14 by means of a pin 122.

The hand grip 18 may be of any desired shape but it has been found for convenience and for better grasping the gun 10 in the position comfortable and effective for most shooters that the hand grip 18 have a rear surface 128 which extends downwardly and forwardly so that the front hand grip 18 is of a generally tapered shape. Finger holes 130 and 132 are provided in the front hand grip for the second and third fingers of a shooter's hand with the trigger finger being comfortably engageable with the trigger 112.

The rear hand grip 20 has a front surface 136 which extends downwardly and forwardly and has a rear surface 138 configurated to form finger recesses 140, 142 and 144 for the second, third, and fourth fingers of the hand of the shooter, and is provided with a trigger finger-hole or opening 146 in an enlarged upper portion 148 of the rear hand grip 20.

Pivoted by means of a pin 150 is another trigger 152 having a finger engaging portion 154 which extends into alignment with the trigger finger opening 146. The trigger 152 has a lever portion 156 to which one end 158 of a rod or cable 160 is attached. The other end 162 of the rod 160 is attached to the projection 102. Hence, actuation of either of the triggers 112 or 152 will cause a pivotal action of the sear mechanism 82 to pivot the firing lever 44.

The gun 10 is provided with a front sight 22 which includes a front sight piece 170 held in place between two sight holders 172 and 174 by means of a pin 176 or the like. Alternatively, the sight can be formed out of a single piece of material or may be integrally formed with the breech 14 during the molding thereof.

The rear sight 24 has a rear sight block 178 into which a rear sight piece 180 is embedded. The sight block 178 may be molded from a synthetic plastic material or may

be formed of other material as may be desired and the rear sight piece 180 is provided with the mirrored surface 26. Of course, the rear sight piece 180 can be constructed from a piece of metal. The rear sight piece 180 is preferably provided with slots 182, 184, 186 and 188 therein which are arranged in a cruciform shape to form cross hairs. Alternatively, cross hairs can be painted, or otherwise applied on the mirrored surface 26.

It has been found advantageous to utilize slots 182, 184, 186 and 188 since by using the slots, the front sight piece 170 can be aligned in the slots with the target, thus facilitating the aiming of the gun above and beyond the sight advantages produced by using the front sight 170 only.

The shoulder rest 25 may be provided with a plurality of ribs 196 which are preferably integrally molded with the breech portion 14. Alternatively, as shown in FIG. 5, in lieu of ribs, grooves 198 may be formed in the shoulder rest 25. The ribs or grooves form a roughened surface which not only enables the gun to be better positioned and supported on the shoulder, but also adds to the pleasing appearance and attractive configuration of the toy gun 10.

In use, a projectile in the form of a dart 28 is inserted into the barrel 12 until the end 68 engages the spring 40 with the collar 58 riding over the cam surface 78 and locking behind the hook 54. The gun is then cocked. For direct firing, the gun can be grasped with two hands in the manner of a sub-machine gun or else may be fired utilizing the rear hand grip 20 in position against the shoulder. However, for better alignment and aiming of the gun, the gun may be grasped with both hands and the front sight 22 aligned with the rear sight 24 by peering through the slots 182, 184, 186 and 188. Then, the trigger 112 is pulled back upon pivoting the trigger and causing the cam surface 118 to depress on the tapered surface 120 pivoting the sear mechanism 82 which causes the horizontally projecting portion 103 thereof to engage the projection 50 pivoting the firing lever 44 about the pin 56 disengaging the hook 54 and releasing the dart collar 58 whereby the spring 40 will push the dart outwardly of the barrel.

The toy gun is especially adapted for use in trick shots such as an "over the shoulder" shot. In this type of trick shot, the shooter will position the gun with the shoulder rest 26, lying on the shoulder of the shooter. Then utilizing the mirrored surface 26, the front sight 22 and the target are aligned in the cross hairs which are either formed by the slots 182, 184, 186 and 188 or alternatively painted or applied on the mirrored surface 26, then the trigger 125 is depressed, causing actuation of the sear mechanism 82 to release the dart.

The gun 10 may, of course, be made in any shape or size as may be desired, the configuration shown being that of a modernistic type toy most appealing to youngsters. The barrel 12 may be provided with an imitation type silencer cap 200 for a realistic touch. The halves of the gun may be secured together such as by pins 202 or may be adhesively bonded or otherwise bolted or secured together.

A latitude of modification, change and substitution is intended in the foregoing disclosure and in some instances some features of the invention will be employed without a corresponding use of other features. Accordingly, it is appropriate that the appended claims be construed broadly and in a manner consistent with the spirit of the invention herein.

What we claim is:

1. A gun comprising an elongated breech portion, a barrel extending forwardly of said breech portion, a firing mechanism in the front end of said breech portion, a front hand grip depending from said breech portion, a rear hand grip depending from said breech portion spaced rearwardly from said front hand grip, said breech portion including a shoulder rest between said front hand

grip and said rear hand grip, and trigger means for actuating said firing mechanism mounted in said front hand grip and said rear hand grip and being connected to said firing mechanism, said firing mechanism including a firing lever pivoted in said breech portion, a sear mechanism for actuating said firing lever, said sear mechanism being pivoted in said breech portion, said trigger means including a front trigger pivotally mounted and engageable with said sear mechanism for moving said sear mechanism to actuate said firing lever, said front trigger being associated with said front hand grip, a rear trigger pivoted in association with said rear hand grip, and means connecting said rear trigger with said sear mechanism for separately actuating said firing lever, a sight on said breech portion rearwardly of said rear hand grip, said sight having a mirrored front surface and formed with a plurality of slots therein forming cross hairs, and a second sight on the front end of said gun for alignment with said slots so that said second sight can be viewed through said slots and can be centered in the cross hairs formed by said slots by viewing said mirrored surface.

2. A gun comprising an elongated breech portion, a barrel extending forwardly of said breech portion, a firing mechanism in the front end of said breech portion, a front hand grip depending from said breech portion, a rear hand grip depending from said breech portion spaced rearwardly from said front hand grip, said breech portion including a shoulder rest between said front hand grip and said rear hand grip, and trigger means for actuating said firing mechanism mounted in said front hand grip and said rear hand grip and being connected to said firing mechanism, said firing mechanism including a firing lever pivoted in said breech portion, a sear mechanism for actuating said firing lever, said sear mechanism being pivoted in said breech portion, said trigger means including a front trigger pivotally mounted and engageable with said sear mechanism for moving said sear mechanism to actuate said firing lever, said front trigger being associated with said front hand grip, a rear trigger pivoted in association with said rear hand grip, and means connecting said rear trigger with said sear mechanism for separately actuating said firing lever, a sight on said breech portion rearwardly of said rear hand grip, said sight having a mirrored front surface, said sight being provided with a plurality of slots therein forming cross hairs, and a second sight on the front of said breech portion for alignment with said slots so that said barrel can be aligned with a target with said second sight and the target being viewed through said slots and said target and said second sight being centered in said cross hairs when viewing said mirrored surface, said shoulder rest being provided with a roughened surface for frictionally retaining said gun on a shoulder of the user.

3. A gun comprising an elongated breech portion, a barrel extending forwardly of said breech portion, a firing mechanism in said breech portion, front and rear hand grips depending from said breech portion, trigger means for actuating said firing mechanism associated with at

least one of said hand grips, a rear sight on the rear part of said breech portion, said rear sight having a mirrored front surface, said rear sight having slots therein forming cross hairs, and a front sight on the front end of said gun for alignment with said slots so that said front sight can be viewed through said slots and can be centered in the cross hairs formed by said slots by viewing said mirrored surface.

4. A gun comprising an elongated breech portion, a barrel extending forwardly of said breech portion, a firing mechanism in the front end of said breech portion, a front hand grip depending from said breech portion, a rear hand grip depending from said breech portion spaced rearwardly from said front hand grip, said breech portion including a shoulder rest between said front hand grip and said rear hand grip, and trigger means for actuating said firing mechanism mounted in said front hand grip and said rear hand grip and being connected to said firing mechanism, said firing mechanism including a firing lever pivoted in said breech portion, a sear mechanism for actuating said firing lever, said sear mechanism being pivoted in said breech portion, said trigger means including a front trigger pivotally mounted and engageable with said sear mechanism for moving said sear mechanism to actuate said firing lever, said front trigger being associated with said front hand grip, a rear trigger pivoted in association with said rear hand grip, and means connecting said rear trigger with said sear mechanism for separately actuating said firing lever, a sight on said breech portion rearwardly of said rear hand grip, said sight having a mirrored front surface, said sight being provided with a plurality of slots therein forming cross hairs, and a second sight on the front of said breech portion for alignment with said slots so that said barrel can be aligned with a target with said second sight and the target being viewed through said slots and said target and said second sight being centered in said cross hairs when viewing said mirrored surface.

5. A toy gun comprising an elongated breech portion, a barrel extending forwardly of said breech portion, a firing mechanism in said gun, a hand grip at the rear of said gun depending from said breech portion for supporting the gun when rested on the user's shoulder and pointed rearwardly, trigger means within said hand grip, a rear sight on the rear part of said breech portion, said sight having a mirrored front surface, said rear sight having slots formed therein forming cross hairs, and a front sight on the front end of said gun for alignment with said slots so that said front sight can be viewed through said slots and can be centered on the cross hairs found by said slots by viewing said mirrored surface.
